UNITED STATES PATENT OFFICE.

EUSTACE ERNEST WIGZELL, OF LONDON, ENGLAND.

WATER-TUBE STEAM-BOILER.

SPECIFICATION forming part of Letters Patent No. 591,445, dated October 12, 1897.

Original application filed January 25, 1897, Serial No. 620,654. Divided and this application filed April 16, 1897. Serial No. 632,436. (No model.)

To all whom it may concern:

Be it known that I, EUSTACE ERNEST WIGZELL, engineer, of Billiter House, Billiter Street, London, England, a subject of Her Majesty the Queen of Great Britain and Ireland, and a resident of Albion Cottage, High Road, Loughton, London, in the county of Essex, England, have invented a new and useful Improvement in Water-Tube Steam-Boilers, of which the following is a specification.

The object of this improvement is to obviate the difficulties hitherto existing in boilers of this class with reference to drawing the tubes when these are arranged at an angle with the vertical and at the same time to increase the general efficiency of the structure as a steam-generator.

As compared with such boilers as commonly constructed my improved boiler possesses the following advantages: The tubes can be withdrawn, plugged, or renewed with the greatest ease. It is most simple in construction. It possesses a very free circulation and great heating-surface, and in case of accident to or bursting of any tube the water would only run out of the section affected, the other sections remaining in working order, so that the boiler could be restored to duty with great rapidity.

My invention consists in certain novel combinations of parts hereinafter set forth and claimed; and in order that the same may be the better understood I herewith proceed to describe embodiments of the invention in connection with two sheets of drawings accompanying this specification as part thereof.

In the drawings I show in Figure 1 an end view, and in Fig. 2 a plan view, of one of my improved boilers with straight vertical angle tubes; and in Fig. 3 a side view, and in Fig. 4 a plan view, of one of my improved boilers with curved tubes, the inclosing walls of the boiler-furnace being shown in section in Figs. 1 and 2 and omitted in Figs. 3 and 4.

Like letters refer to like parts in all the figures.

In both arrangements I locate with proper reference to one or more fire-chambers A, Fig. 1, groups (one or more) of water-tubes, 50 each group having at top what are herein termed "end boxes" B in the form of square

tubes parallel with each other and conveniently in contact with each other, within which the upper ends of the tubes C are expanded, the top and bottom surfaces of said end boxes 55 B being at an angle to the horizontal and said top surfaces being provided with hand-holes D, indicated in the drawings by their stoppers, in line with the individual tubes. Like end boxes E unite the tubes C into sections at bottom and afford access by their hand-holes D to the lower ends of the tubes. Short connecting-tubes F, parallel with each other, extend endwise from the upper end boxes B into steam or water chests G. Flue- 60 spaces for the passage of flame or heat are provided between said tubes C and also between said connecting-tubes F. Branch pipes H, each provided with a stop-cock I, extend endwise into the lower end boxes E from horizontal inlet-pipes J at bottom. A padlocked rod K, Fig. 3, extending through the gage-holes in the squares of the stop-cocks (shown at I in Fig. 1) insures the opening of all the stop-cocks before firing the furnace, and a 65 circulating-pipe L conveniently connects, if necessary, the bottom of the steam or water chests with the inlet-pipes J, as best shown in Fig. 3.

The tubes C, connecting a pair of the end boxes B and E, constitute, with the latter, a distinct section, segregable as a whole, and the boiler is given the required capacity by employing a greater or less number of such sections. The stop-cocks I facilitate locating 80 the section in which a break has occurred and provide for stopping the flow of water into and through such section from the remainder of the boiler. The hand-holes D provide for withdrawing or plugging a damaged tube without disturbing the remainder of its section.

In the improved boiler shown in Figs. 1 and 2 the end boxes B and E have corrugated vertical sides, their corrugations fitting into 85 each other, as shown in Fig. 2 at B' B', whereby adjoining end boxes are interlocked with each other to a sufficient extent for mutual support. The end boxes E strike out from each side of the fire-chamber A and slope upward. The upper end boxes B are arranged at the same angle to the horizontal. The tubes C 90 100

are straight and at right angles to the end boxes. The fire passes right and left in among the tubes C and upward between and around the connecting-tubes F, which lead from the 5 corrugated end boxes B into the steam or water chests G, which in this boiler are arranged horizontally at the outer ends of said upper end boxes B and at right angles thereto. Baffle-plates M, Fig. 1, preferably lead or 10 direct the flames as they pass from the fire-chamber A between the tubes C, and a steam-pipe N connects the pair of steam or water chests G. Suitable side and end walls are represented at O and P, Figs. 1 and 2, and a 15 vertical uptake at Q.

In the arrangement represented by side and plan views in Figs. 3 and 4 the end boxes B and E, in the form of square tubes, each have two sides facing downward and two sides 20 facing upward, and the tubes C are suitably curved. These tubes are expanded within the upper end boxes B and lower end boxes E in the same manner as the straight tubes above described, and the end boxes are 25 provided with hand-holes D, as aforesaid, so that the curved tubes C can be plugged or drawn individually through the upper end boxes B. The connecting-tubes F lead from the upper 30 end boxes B into a single steam or water chest G. The branch tubes H, stop-cocks I, inlet-pipe J, padlocked rod K, and circulating-pipe L, Figs. 3 and 4, have already been described.

In making a continuous boiler I can place 35 two groups, such as are formed by the corrugated end boxes B and E, straight tubes C, and connecting-tubes F, Figs. 1 and 2, with or without the baffle-plates M, on the respective sides of a single steam or water chest G, 40 connecting the upper end boxes B at their highest ends by said tubes F direct to the steam or water chest on each side of the latter, and passing fire or heat in among the tubes C and between the connecting-tubes F 45 to the uptake in any approved manner. A similar arrangement can also be made with the curved tubes shown in Figs. 3 and 4.

My boiler can also be made double-ended either by placing two sets, such as above described, back to back or by introducing a 50 fire-brick partition in the center, so that fire-doors can be fitted to each end.

All patentable combinations of parts hereinbefore described which are not hereinafter claimed are disclaimed in favor of the specification forming part of my application for United States Letters Patent filed January 25, 1897, Serial No. 620,654, of which my present application is in part a division. 55

My present improvement is intended to be 60 confined to the means hereinbefore described for limiting the escape of water in case of accident and facilitating the withdrawal of the individual water-tubes.

Having thus described the said improvement, I claim as my invention and desire to patent under this specification—

1. In a water-tube steam-boiler, the combination substantially as hereinbefore specified of withdrawable water-tubes in a group 70 or groups, made up of segregable sections, and having end boxes in the form of square tubes at the top and bottom of each section arranged with top and bottom surfaces at an angle to the horizontal, and provided with 75 hand-holes in the tops of the upper end boxes and bottoms of the lower end boxes in line with the individual tubes, an inlet-pipe at the bottom of each group, branch pipes connecting said inlet-pipes with the lower end 80 boxes, and means for stopping said branch pipes individually.

2. The combination, in a water-tube steam-boiler, of a horizontal inlet-pipe at the bottom, end boxes at the bottom of each section, 85 branch pipes extending from said inlet-pipe into the adjacent ends of said end boxes individually, and a stop-cock in each of said branch pipes, substantially as hereinbefore specified. 90

3. The combination, in a water-tube steam-boiler, of a horizontal inlet-pipe at bottom, end boxes at the bottom of each section, branch pipes extending from said inlet-pipe into the adjacent ends of said end boxes individually, a stop-cock in each of said branch 95 pipes having a gage-hole in its square, and a padlocked rod which occupies said gage-holes when all the stop-cocks are open, substantially as hereinbefore specified.

EUSTACE ERNEST WIGZELL.
